Primary Examiner — Darcey E Gottschalk(74) *Attorney, Agent, or Firm* — Boyle Fredrickson, S.C.(57) **CLAIM**

The ornamental design for a disposable cup lid, as shown and described.

DESCRIPTION

FIG. 1 is an isometric view of a disposable cup lid incorporating my new design, viewed from in front of, above, and from the right side thereof;

FIG. 2 is a top plan view thereof;

FIG. 3 is a bottom plan view thereof;

FIG. 4 is a left side elevation view thereof;

FIG. 5 is a right side elevation view thereof;

FIG. 6 is a front side elevation view thereof;

FIG. 7 is a rear side elevation view thereof with the flap in an unfolded position; and,

FIG. 8 is an isometric view thereof viewed from in front of, below, and from the right side thereof.

The dot-dash broken lines shown in FIGS. 1, 2, 3, and 8 illustrate boundaries of the claimed design, the evenly spaced broken lines depict portions of the disposable cup lid, and all broken lines form no part of the claimed design.
